PORTABLE POLISHING MACHINE

Frank R. Feenan, Detroit, Mich.

Application June 12, 1933, Serial No. 675,425

2 Claims. (Cl. 51—170)

The present invention pertains to a novel device for obtaining smooth clean surfaces, and more particularly to a portable cleaning, polishing, and buffing machine for treating automobile bodies.

The primary object of the present invention is to provide a cleaning and polishing machine wherein an abrasive member is rotatably supported and driven in a manner whereby the portion of the abrasive member which contacts with the surface being treated has a linear path of movement. In this connection the abrasive member is provided in the form of an endless band supported on a pair of rolls, one of which is adapted to be driven by a flexible shaft and the other of which is adjustably supported and provided with means for adjusting the same in order that the band may be easily removed and replaced, and the rolls spaced a distance apart to provide sufficient tension on the band to eliminate slippage.

Another object of the present invention is to provide a cleaning and polishing machine including a pair of spaced rolls over which a band is placed to be rotated by driving one of the rolls. The rolls are so spaced to hold the band with a straight run extending from one roll to the other, which straight run may be bent to assume the same shape as a surface with which it is brought into contact. In other words the abrasive supporting band may be flexed to provide a linear working movement relative to a curved surface.

Another object of the present invention is to provide a cleaning and polishing device including a flexible, cushion-like support for an abrasive band, or a polishing band and eliminate possibility of grooving or scratching a surface by uneven application of pressure thereon during the process of manually bringing the abrasive band into contact with a surface to be treated while the band is being rotated at a high rate of speed.

Another object of the present invention is to provide a cleaning and polishing device comprising a rotatable band with a flexible or cushion-like support, and means for supporting and rotating the same so that it may be easily manipulated in contact with a surface to be finished, and so that the band may be quickly and easily removed and replaced.

With the above and other ends in view, the invention consists in matters hereinafter set forth and more particularly pointed out in the appended claims, reference being had to the accompanying drawing, in which—

Figure 1 is a side elevation with a part of the casing in cross section;

Fig. 2 is an end elevation;

Fig. 3 is a cross section taken on the line 3—3 of Figure 2;

Fig. 4 is a cross section taken on the line 4—4 of Figure 3;

Fig. 5 is a cross section taken on the line 5—5 of Figure 3;

Fig. 6 is a cross section taken on the line 6—6 of Figure 3; and

Fig. 7 is a cross sectional detail.

Like characters of reference are employed throughout to designate corresponding parts.

The numeral 1 indicates the top wall of a casing having side walls 2 and 3 secured thereto, the side wall 3 being provided with a removable portion 4. Adjacent one end of the casing the side wall 2 and the removable portion 4 of the side wall 3 are provided with slots 5 in which a shaft 6 is slidably mounted. The outer ends of the shaft 6 receive nuts 7 which may be tightened into contact with the side walls in order to prevent sliding movement of the shaft in the slots. Rotatably journaled on the shaft 6 is a roll 8 having side flanges 9.

Adjacent the other end of the casing a shaft 10 is rotatably journaled in the side wall 2 and the removable portion 4 of the side wall 3 and has one end projecting through the side wall 2 upon which a gear 11 is secured, such as by the pin 12. A roll 13 is mounted on the shaft 10 to rotate therewith, a key being designated by numeral 14 as an illustration of means for connecting the roll to the shaft. The roll 13 is preferably of a diameter corresponding to the diameter of the roll 8, and is formed with peripheral side flanges 15.

Means is provided for rotating the gear 11 in order to rotate the shaft 10 and roll 13, and the means includes a transverse shaft 16 suitably journaled in the casing and having a spur gear 17 secured thereon externally of the casing and meshing with the gear 11. Also secured on the shaft 16 is a bevel gear 18 that meshes with a bevel gear 19 that is rotatably journaled in a housing 20 that is secured in suitable fashion to the casing 1. The housing 20 serves to enclose and protect all the above described gears. The bevel gear 19 is connected to a flexible drive member 21 which is adapted to be rotated by any suitable motor or engine.

The side wall 2 and the removable portion 4 of the side wall 3 are provided with grooves 22 in which are slidably received rack bars 23 having

loops 24 through which opposite ends of the slide-
able shaft 6 extend. Pinions 25 are mounted on
a transverse shaft 26 to mesh with the racks 23.
On one end of the shaft 26 is received a lock nut
5 27 which is adapted to be screwed into engage-
ment with the side wall 2 in order to prevent ro-
tation of the shaft 26, and on the other end of
the shaft is formed or secured a head 28 suit-
able for receiving a wrench for applying manual
10 pressure thereto in a manner to rotate the same.

Received on the two rolls 8 and 13 is a power
transmission belt 29 which may be of any con-
ventional or well known construction such as
15 leather, rubber, or canvas. Mounted on the belt
is a band 30 formed of material such as sponge
rubber, and surrounding the band 30 is a band
31 of such material as soft felt. The sponge rub-
ber band 30 and the felt band 31 are preferably
20 secured together in the manner illustrated in
Fig. 7 wherein a thread 32 is imbedded in the felt
band so that the run 33 is positioned beneath the
surface of the felt band.

In using the present device the nuts 7 are loos-
ened to permit sliding movement of the axle 6 in
25 the slots 5 so that the belt 29, sponge rubber band
30, and the felt band 31 may be trained over the
two rolls 8 and 13 in the manner illustrated in
Fig. 3. The head 28 on the shaft 26 is then ro-
tated by manual pressure to rotate the pinions
30 25 and thus move the rack 23 to slide the shaft
6 in the grooves 5 in a direction to carry the roll
8 away from the roll 13 and place tension on the
belt 29. Upon rotation of the flexible drive mem-
ber 21 the bevel gears 19 and 18 are rotated, the
35 latter causing rotation of the spur gear 17 which
meshes with and rotates the gear 11. Rotation
of the gear 11 results in rotation of the roll 13
and results in movement of the belt 29 around
the two rolls 8 and 13. The sponge rubber band
40 30 and the felt band 31 are carried by the belt 29
and by holding the felt band 31 in contact with
a surface the latter may be polished or buffed.

It is well known in the art that polishing and
45 buffing members are treated in some cases by
coating the same with glue and applying abrasive
thereto in the form of a powder. It will be un-
derstood that the present invention contemplates
such treatment of the felt band if the work to be
50 performed requires use of an abrasive. It is also
contemplated that emery cloth bands may be
mounted on the felt band 31 for certain types of
work.

It will be observed that the sponge rubber
55 band 30 provides a cushion-like support for the
felt band 31 which is flexible so that in the event
of an uneven application of pressure the surface
of the work will not become deeply scratched or
grooved. Furthermore the cushion-like support

for the flexible band permits use of the device on
surfaces which are not flat, such as the curved
portions of an automobile body.

As designated at 34 handles may be attached
to the top wall 1 of the casing by means of lugs
80 35 and nuts 36 so that by loosening the nuts the
handles may be adjusted by pivotal movement
relative to the lugs 35 to suit the convenience of
the operator.

Although a specific embodiment of the present
invention has been illustrated and described, it is
to be understood that various changes may be
made in the details of construction within the
scope of the appended claims and without de-
parting from the spirit of the invention, and such
changes are contemplated.

What I claim is:

1. A device of the character described comprising
a casing having parallel side walls in which
longitudinal slots are formed adjacent to one end
thereof, a driven roll mounted adjacent to the
other of said casing with its axis fixed relative
thereto, an axle in said casing and having its op-
posite ends extending through said slots in said
casing, releasable securing members mounted on
the outer ends of said axle and adapted to fric-
tionally engage said side walls to prevent move-
ment of said axle within said slots, a roll rotat-
ably mounted on said axle, an endless member
trained over said rolls, and manually operable
means in said casing for moving said axle relative
to said slots when said securing members are
released, said last named means comprising rack
members having ends attached to said axle, a
shaft extending transversely through said casing,
95 gears on said shaft meshing with said racks, and
means for manually rotating said shaft.

2. A device of the character described com-
prising a casing having parallel side walls in
which longitudinal slots are formed adjacent to 115
one end thereof, a driven roll mounted adjacent
to the other end of said casing, with its axis fixed
relative thereto, an axle in said casing and hav-
ing its opposite ends screwthreaded and extend-
ing through said slots, nuts received on said 120
screw-threaded ends and adapted to frictionally
engage said walls to prevent movement of said
axle in said slots, a roller rotatably mounted on
said axle, an endless member trained over said
rolls, manually operable means carried by said 125
casing for moving said axle relative to said slots
when said nuts are released, said last named
means comprising rack members having ends at-
tached to said axle, a shaft extending transverse-
ly through said casing, gears on said shaft mesh-
ing with said racks, and means for manually ro-
tating said shaft.

FRANK R. FEENAN.
